LOCKING DEVICE WITH SLIDER

Lajos Steiner, Neutral Bay, New South Wales, Australia

Application June 24, 1952, Serial No. 295,369

2 Claims. (Cl. 24—205)

1

This invention relates to locking devices for connecting, attaching or coupling parts and structures, and more particularly edges of such parts and structures in a releasable manner.

The present invention has been devised to provide means to lock releasably edges of any selected length. A further purpose is to furnish a positive and safe form for fastening or coupling edgewise parts, structures or fabrics in a releasable manner. A still further purpose is to provide a releasable locking and fastening device which lends itself to a wide range of application in connection with both rigid and flexible structures.

According to the invention, the device consists broadly of three parts: a first element containing a jaw portion with an opening into the jaws at one side edge thereof, such element extending along the side of the structure to which the device is to be fitted, said jaw portion containing also locking means; a second element extending along the side of the part to be attached to said structure, having means to engage in the said locking means of the first element; and a third, operating member slidably mounted on said first element which releases the first and second elements. The closing action is effected by simply pressing the second edge element into the jaw of the first edge element, while the opening action is performed by moving the third, operating member edgewise in either direction.

In order that the invention may be fully understood, reference is made to the accompanying drawings wherein:

Fig. 1 is a view in perspective of the first edge element;

Fig. 2 is a similar view of the second edge element;

Fig. 3 is a similar view of the third, operating element;

Fig. 4 is a similar view of the compensating member slidably located inside of the first edge element;

Fig. 5 is a similar view of the housing of the second edge element;

Fig. 6 is a similar view of a modified form of the second edge element, not requiring separate housing;

Fig. 7 is a sectional elevation of the entire assembly;

Fig. 8 is a sectional elevation of the first and second edge elements locked together;

Fig. 9 is a sectional elevation of the first and second edge elements, with locking means disengaged;

2

Fig. 10 is a sectional elevation of the first and second edge elements in the process of separation;

Fig. 11 is a sectional elevation of portions of the first edge element and the modified form of the second edge element (Fig. 6) in locked position.

Referring to Figures 1 to 11 inclusive, the first edge element *a* is roughly of rectangular shape, having face *a*2, lip *a*3, chamfer *a*9, side face *a*10, and may be made of metal or plastic material.

10 The second edge element *b*, also made of metal or plastic, has ridge *b*1 capable of engaging into said first edge element *a*, and also has a second ridge *b*5 to locate it in housing *g*. This element can be formed of any number of separate, identical pieces, and is housed in housing *g*, having cavity *g*1 and lip *g*2 to retain said second edge element *b*, held in place by spring *h*, which may be a coil, or preferably leaf spring.

However, by making second edge element *b* of 20 sufficiently springy material, it may be combined with the housing *g*, eliminating the need for separate spring or springs *h*. Such a modification and combination is shown in Fig. 6, designated as *k* which thus would take the place of the entire 25 second edge element combination consisting of the parts *b*, *g* and *h*.

Compensating member *e* shown in Fig. 4 consists of any number of separate, identical units, 30 slidably located inside of first edge element *a*, and held in place by spring or springs *f* which might be coil, or leaf spring or springs.

Sliding or operating member *c* shown separately in Fig. 3 is slidably mounted on the first edge element *a*.

To fully understand the operation of the device and the functions of each individual part, it is advisable to refer to Fig. 8 first wherein the sectional view shows two edge elements in locked position. Ridge *b*1 of the second edge element *b* 35 is trapped against face *a*2 of first edge element *a* and face *b*9 of second edge element *b* is blocked by face *e*2 of compensating member *e*; ridge *b*5 is retained by lip *g*2 of housing *g*. Thus the two edges are firmly and positively united and cannot be opened without other means, which fact makes it 40 easy to provide special locking arrangements with a suitable key, preventing unauthorized opening.

By varying length *x* shown in Fig. 2 and Fig. 6 on the second edge element *b* a considerable degree 45 of tolerance may be achieved without effecting the firmness of the locking device.

The ends of first edge element *a* and the housing *g* are closed, or blocked by suitable means. First edge element *a* may be attached to one edge 50 of the structures to be coupled, by welding, rivet-

ing, screws or otherwise, and similarly the housing *g* of the second edge element is attached to the other edge to be coupled, or united with the first edge.

Fig. 7 shows the assembly in operation. Compensating member *e* is dislodged by sliding member *c*, and actuated by spring *f*, it is ready to return and block said second edge element *b* from reengagement. Second edge element *b* is almost fully dislodged by said sliding member *c*. As the sliding member *c* releases compensating member *e* and second edge element *b*, the open position shown in Fig. 9 will be reached, from which the two parts can be pulled apart. The opening is positive in the sense that face *e8* of the compensating member *e* now opposes face *b7* of the second edge element *b* and under pressure by spring *f* will lead the second edge element *b* as far out as necessary to prevent it from re-engaging.

To close the device, the two sides merely need to be pushed or slammed together as shown in Fig. 10. Ridge *b1* of second edge element *b* abuts against chamfer *a9*, and is forced down. Rounding or chamfer *b8* starts to engage the compensating member *e* dislodging it until ridge *b1* passes face *a3*. Actuated by spring *h* and by rounding or chamfer *e6* of said compensating member *e*, said second edge element *b* snaps into closed position shown in Fig. 8.

To open, the sliding or operating member *c* is pushed in either direction. Chamfer or rounding *c6* of said operating member *c* contacts compensating member *e* and overcoming resistance of spring *f*, gradually dislodges compensating members *e* one after the other. As soon as face *e2* of said compensating member *e* clears face *b9* of the second edge element *b*, chamfer or rounding *c7* of sliding member *c* contacts ridge *b1* and overcoming resistance of spring *h*, gradually pushes second edge elements *b* into open position, one after the other and the resultant position is shown in Fig. 9.

It is believed that from the above description and attached drawings those skilled in the art

will fully understand the construction and operation of the device which is readily adaptable for a great variety of applications, including watchbands, handbags, boxes, and luggage.

Changes in the form or size of parts, or their arrangement may be made, or parts may be combined, without departing from the spirit of the invention which is not limited to the specific construction shown and described, and from which departures may be made within the scope of the accompanying claims.

What I claim is:

1. A locking device of the type described, having, in combination, a first edge element, a second edge element and a sliding member; said first edge element consisting of an elongated strip of material divided by a longitudinal opening, having on its inside a longitudinal recess, and having a longitudinal lip, and having inside said longitudinal recess a plurality of resiliently supported locking members; said second edge element consisting of a plurality of members resiliently held by a longitudinal housing, said members having ridges engaging into the lip of said first edge element and locked in place by said locking members inside said longitudinal recess of said first edge element; said sliding member being slidably mounted on the outside of said first edge element and having guides protruding inside said longitudinal recess, displacing said resiliently supported locking members and disengaging said ridges of said second edge element from said lip of the first edge element.

2. A locking device as described in claim 1, wherein the locking members are formed in a series of parts of substantially right angular construction with the edges chamfered.

LAJOS STEINER.
